UNITED STATES PATENT OFFICE.

CARL M. DEADWYLER, OF DAYTON, OHIO.

FURNITURE-BRACE.

1,297,330.

Specification of Letters Patent. Patented Mar. 18, 1919.

Application filed October 4, 1918. Serial No. 256,848.

To all whom it may concern:

Be it known that I, CARL M. DEADWYLER, a citizen of the United States, and resident of Dayton, in the county of Montgomery and

5 State of Ohio, have invented certain new and useful Improvements in Furniture-Braces, of which the following is a specification.

The present invention relates to furniture braces and more particularly to the type for drawing together the four corners of a furniture structure such as a bed frame, chair, or the like, so that all looseness in the joints of the structure is eliminated, an object of this invention being to provide a tightening 10 device which will be so engaged by the brace wires that a slipping of the wires on the device will be permitted without any cutting of such wires, thus enabling the wires to be subjected to greater tensile strains. Another 15 object of the invention is to provide a construction which will permit the use of either two wires, each of which has a slipping connection on the tightener, or the use of three or four wires with such slipping action, and 20 all without producing any cutting of the wires. Another object of the invention is to provide an anchoring device for securing the ends of the wires to an upright, such as a corner post, such anchoring device being adjustable to connect with corner posts of different diameters.

30 To these and other ends, the invention consists of certain parts and combinations of parts all of which will be hereinafter described, the novel features being pointed out in the appended claims.

In the drawings:—

Figure 1 is a plan view of a metal bed frame equipped with the present invention; 40 Fig. 2 is a detail view of a yoke of the tightening device, showing one wire connected to such yoke;

Fig. 3 is a detail view of a yoke of the tightening device, showing two wires connected to such yoke;

Fig. 4 is a detail view of one of the yokes looking in the direction of the axis of the screw secured to such yoke;

Fig. 5 is a view of the under side of the 50 yoke with the wires removed;

Fig. 6 is a side view of one of the yokes with the wires removed;

Fig. 7 is a section on the line 7—7, Fig. 8, through one of the anchoring devices;

55 Fig. 8 is a side elevation of one of the an-

choring devices attached to a corner post; and

Fig. 9 is a detail perspective view of one part of the anchoring devices.

In the embodiment of the invention shown, 60 three brace wires 1, 2 and 3 are employed, the first two being connected to one of the yokes of the tightening devices, while the other brace wire is connected to the other yoke of the tightening device. It is apparent, however, that both yokes may have only one wire connected to each of them, or two wires connected to each of them. In metal bedsteads in particular it is desirable to employ only one brace wire for each yoke, as 65 the heavy box-like spring and mattress sag at their sides near the center and will rest upon the brace wires if the latter are connected to the sides of the bed frame. In wooden bedsteads, however, the sides of the 70 bed frame will bend outwardly under the tension produced by the tightening device, and it is desirable to restrain this outward bending by connecting the brace wires to the sides. When two wires are used, as shown 75 in the illustrated embodiment, at one end of the bed, each of said wires is secured at one end to an anchoring device 4, such as an eye on the side 5 of the bed frame, while the other end is secured to an anchoring device 80 attached to the corner post. Any suitable anchoring device may be employed, but it is preferred to use anchoring devices forming one of the features of this invention, such anchoring device being especially adapted 85 for use on the corner post of metal bedsteads.

The improved anchoring device in this illustrated embodiment comprises a hook 6 or other brace wire securing means projecting from a wedge-shaped portion 7 having 90 a portion 8 which projects from opposite sides of the wedge portion 7, and has at its opposite edges laterally-turned portions 10 spaced from the side face of the wedge portion 7 to provide pockets. Flanges 11 also 100 project from the under side of the wedge portion 7 to form rests for a clamping member which is received within the pockets formed by the flanges 10. The clamping member embodies two converging side walls 105 12 connected by a wall 13, the convergence of these side walls corresponding to the taper of the wedge portion 7, so that when the side walls 12 are supported upon the rests 11 they will be connected above the tapered 110

portion 7 by the connecting wall 13. This clamping member serves to firmly hold a flexible strip or tape 14 to the anchoring device and about the corner posts 9. To this end the ends of the tape or strip 14 are extended over the laterally-turned portions 10 on opposite sides of the abutting portion 8, then around the proximate ends of the converging walls 12 of the clamping member, then over the anchoring faces of said walls between such walls and the wedge portion 7, and then about the opposite ends of the walls 12 and over the outer faces of said walls, so as to lie between the latter and the laterally-turned portions 10, which merely act to cover and not to clamp the strip. With this arrangement the ends of the tape or anchoring strip 14 are firmly secured to the anchoring device. The clamping member 12 may be readily disconnected from or connected to the hook carrying portion of the anchoring device by moving the clamping member outwardly with relation to said hook carrying device. The clamping member and hook carrying device are normally held together against accidental displacement when tension is on the strip 14 by an overhanging lip 15 which projects from the abutting portion 8 and cooperates with the upper surface of the connecting wall adjacent said abutting portion. When this tension is removed, sufficient looseness in the parts permits the clamping member to move outwardly on hook carrying device to be freed from the overhanging lip. It is apparent that the tape or strip 14 may be made of any suitable length and in this way the anchoring device is adapted for corner posts of different diameters.

40 The tightening device in this instance comprises two yoke members each of which may have a screw portion in the form of a screw threaded stem 16 projecting therefrom, the screw portions of the two members being right and left and being connected by a turnbuckle 17 which, when turned in one direction, brings the yoke members together, and when turned in the other direction tends to separate the yoke members.

45 50 Of course, any other suitable means may be employed for connecting the yoke members. Each yoke member, in this instance, is so formed that either one or two wires may be engaged with such member. It is apparent, however, that the invention is not limited to a construction which will permit the use of either one or two wires with the yoke member, but that it is within the scope of this invention to provide a yoke construction with which only one brace wire may be connected. When only one wire is used, as shown at the left hand side of Fig. 1, such wire enters into contact with the yoke member at one side of said member and maintains such contact until it issues from the

yoke member at the opposite side. This result is secured by providing a groove having diverging end portions 18 which lie in one plane, and are connected together at their proximate ends by groove portions which 70 project from or lie to one side of the plane of the diverging groove portions. These connecting groove portions embody a curved portion 19, the plane of such curve being substantially parallel to the plane of the diverging groove portions 18, and the concave side of such groove portion 19 being disposed toward the converging ends of the diverging groove portions 18, the ends of said portion 19 being connected with such converging ends by two groove portions 20. These groove portions 20 are also curved and form lateral connections between the diverging groove portions 18 and the curved portions 20. With this arrangement it will 80 be seen that a wire 3 entering one of the groove portions 18 proceeds to the inner end of such portion, then turns laterally and upwardly on a curve, then proceeds horizontally on a curve through the groove portion 90 19 to the opposite curved connecting groove portion 20, downwardly through such portion 20 to the other diverging groove portion 18, and through and out of the latter. To adapt the yoke member for connection with 95 two wires, as shown at the right hand side of Fig. 1, the yoke member is provided with a groove portion 21 which connects the two groove portions 20. With this arrangement, a wire 1 or 2 entering the outer end of the 100 groove portion 18 will pass through said groove portion and into the groove portion 20, and finally proceed from the yoke at the opposite side of said groove portion 20. The other brace wire will enter the opposite 105 groove portion 18 and also enter into the groove portion 20 to one side of the first named wire proceeding from the yoke member in the opposite direction.

From the foregoing it will be seen that 110 there has been provided an anchoring device which will permit the brace wires to be readily connected to corner posts of beds or other furniture of different diameters. A tightening device is employed which has its yoke 115 member so formed that no sharp corners are provided which will tend to cut the brace wires. The brace wires have a long and extended bearing upon the tightening device, and the wire receiving grooves are so formed 120 that each yoke may have either one or two wires connected thereto.

What I claim as my invention and desire to secure by Letters Patent is:—

1. A tightening yoke for furniture braces 125 comprising a head formed with a wire-receiving groove having diverging portions lying in one plane, and portions connecting the diverging portions and lying to one side of the plane of said diverging portions. 130

2. A tightening yoke for furniture braces comprising a head formed with a wire-receiving groove having diverging portions lying in one plane, a curved portion lying to one side of the plane of the diverging portions with its plane parallel with the plane of the diverging portions, and curved portions connecting the first named curved portions with the diverging portions.
- 10 3. A tightening yoke for furniture braces comprising a head formed with a wire-receiving groove having diverging portions lying in one plane, a curved portion lying to one side of the plane of the diverging portions with its plane parallel with the plane of the diverging portions, two grooved portions between the ends of the first-named curved portion and the diverging portions, said head also having a wire-receiving groove connecting the last two named grooved portions.
- 15 4. In a furniture brace, a tightening yoke having a head formed with a wire-receiving groove provided with diverging portions lying in one plane, and portions connecting the proximate ends of said diverging portions and lying to one side of the plane of said diverging portions, combined with a brace-wire extending through said groove and bearing against the yoke member from one end of the groove to the other.
- 20 5. A tightening yoke for furniture braces comprising a head formed with two diverging grooved portions and two grooved portions connecting proximate ends of said diverging grooved portions, one of said connecting grooved portions lying substantially in the plane of the diverging grooved portions and the other of said connecting grooved portions lying to one side of the plane of said diverging grooved portions whereby either one or two brace wires may be connected to the tightening yoke.
- 25 6. An anchoring device for securing brace wires to furniture comprising a brace wire 45 securing means, a wedge shaped portion on said brace wire securing means, a clamp for coöperation with said wedge shaped portion, and a flexible strip for passing about the furniture, held between the wedge-shaped 50 portion and the clamp.
- 10 7. An anchoring device for securing brace wires to furniture comprising a brace wire securing means, a wedge shaped portion on said brace wire securing means, flanges projecting 55 from opposite sides of the wedge shaped portion, a clamp arranged to co-operate with the wedge shaped portion, and a strip for passing about the furniture, having its ends arranged between the wedge shaped portion and the clamp.
- 15 8. An anchoring device for securing brace wires to furniture comprising a brace wire securing means, a wedge shaped portion, a portion projecting beyond the sides of the 65 wedge shaped portion and having laterally-turned converging portions at opposite sides spaced from the wedge shaped portion, a clamp formed of two converging walls arranged to coöperate with the wedge shaped 70 portion and adapted to enter the space between said wedge shaped portion and the laterally-turned converging portions, and a flexible strip having its ends lying between the clamping member and the wedge shaped 75 portion and also between said clamping member and said laterally-turned converging portions.

CARL M. DEADWYLER.
